US00D864281S

(12) United States Design Patent (10) Patent No.: US D864,281 S
(45) Date of Patent: * Oct. 22, 2019

(54) SELFIE STICK

(71) Applicant: BREEZE.IT

UNTERNEHMERGESELLSCHAFT
(HAFTUNGSBESCHRÄNKT), Witten
(DE)

(72) Inventor: Fusheng Wang, Shenzhen (CN)

(73) Assignee: BREEZE.IT

UNTERNEHMERGESELLSCHAFT
(HAFTUNGSBESCHRÄNKT), Witten
(DE)

() Term: 15 Years

(21) Appl. No.: 35/504,826

(22) Filed: Apr. 5, 2018

(80) Hague Agreement Data

Int. Filing Date: Apr. 5, 2018

Int. Reg. No.: DM/100830

Int. Reg. Date: Apr. 5, 2018

Int. Reg. Pub. Date: May 4, 2018

(30) Foreign Application Priority Data

Jan. 22, 2018 (CN) 2018 3 0029470

(51) LOC (12) Cl. 16-05

(52) U.S. Cl.

USPC D16/243

(58) Field of Classification Search

USPC D16/219, 237-250; D14/224, 229, 238,
D14/251, 253

CPC G03B 17/56; G03B 17/561-568
